UNITED STATES PATENT OFFICE.

EUGENE W. SCHNEIDER, DECEASED, LATE OF NEW YORK, N. Y., BY ELIZABETH C. SCHNEIDER, EXECUTRIX, OF NEW YORK, N. Y.

DEVICE FOR AIDING THE HEARING.

1,219,671.

Specification of Letters Patent. Patented Mar. 20, 1917.

Application filed September 9, 1916. Serial No. 119,182.

To all whom it may concern:

Be it known that EUGENE W. SCHNEIDER, deceased, late a citizen of the United States, and resident of Jamaica, city of New York, 5 county of Queens, State of New York, did invent certain new and useful Improvements in Devices for Aiding the Hearing, of which the following is a full, clear, and exact description.

10 This invention relates to improvements in telephonic devices for aiding the hearing, of the type shown in my former Patent, No. 1,192,122.

15 The objects of this invention reside in the simplification and improvements of the transmitter shown in the aforesaid patent. Other objects reside in the provision of an improved and simplified rheostat than the previously shown rheostat. Other objects 20 will be pointed out in detail in the accompanying specification.

In the drawings:

Figure 1 shows a rear view of the transmitter with cover plate over the switch removed.

25 Fig. 2 is a front view with the front cover which carries the sound concentrating shells, removed. This view shows the arrangement of the coils of resistance wire which form a 30 part of the rheostat.

Fig. 3 is a view similar to Fig. 2 but with resistance coils, the microphone electrode and certain other parts removed to show the construction.

35 Fig. 4 is a central section view of the transmitter.

In more detail, the transmitter is provided with clip terminals 10—11 which may be directly mounted upon a battery as shown 40 in the patent previously referred to or which may be connected to the battery by wires as shown. The casing of the transmitter is composed of a box 13 and a screw cover 14 which carries sound concentrating shells 15 45 of the type shown in Patent to Schneider, No. 1,192,123. To prevent opening of the casing by the unskillful user, the cover is locked on the box by a pointed device 16 controlled by an eccentric device 17. With 50 the pointed device and eccentric in the position shown in Figs. 2 and 4, the cover is free to be removed but by turning a concealed screw 18 the eccentric can be turned and the point 16 can be forced out against the contiguous threads of the cover so that if the

attempt is made to unscrew the latter, the point will bite into the metal (preferably aluminum) and so prevent further turning. The head of the screw 18 is concealed under a cover plate 19 as shown in Fig. 4. When 60 the cover plate 19 is removed the head of screw 18 is accessible so that a screw driver may be applied to turn the eccentric and retract the pointed device. Inside the transmitter casing and fastened to a boss 20 which 65 is insulated from and secured to the casing is a microphone electrode 25 in the usual form of a carbon disk having pockets containing globular carbon in contact with the vibrating diaphragm 26. The boss and electrode are electrically connected through their fastening screw. The boss also forms a support for a bracket 27 which is insulated from both boss and casing. This insulated bracket carries a binding post 28 to which 70 leads a wire 29 extending to the receiver (not shown). A conducting strip 30 connects the binding post 28 with one end of a resistance wire. This wire is looped in the form of a series of coils 31 which are wound 75 upon an arcuate insulating strip which is fastened to the interior of the casing. The coils 31 are electrically connected to a series of taps 32 which extend through an arcuate insulating block 33 and which have rounded 80 contact points 34 thereon which are concentric about the center of the boss as shown in Fig. 1.

The resistance switch 35 is of spring metal and is pivotally held against the end 90 of the boss by a screw. The switch has a capped end which makes contact with the contact points 34 and the width of this end is such that in shifting from one contact to another the switch bridges two contacts 95 thereby never breaking the circuit through the resistance coil. This prevents the annoying clicks which would occur if the circuit were broken during the operation of the rheostat. One end of the switch 35 carries a handle 36 which projects through an arcuate slot in the coverplate 19 in accessible position to a user of the instrument.

Inside the casing are two arcuate shaped strips 37 and 38. Strip 37 is insulated from the casing and serves to conduct current from the terminal 10 to wire 39 which leads to one side of the receiver. Strip 38 is in electrical contact with the casing and connects with the opposite terminal 11.

The circuit through the transmitter is as follows. Current flows in at terminal 10 (Fig. 3.) through 37, 39 through receiver back through wire 29, binding post 28, 30 and into coils 31 thence through one of the taps 32, contacts 33, to switch 35 which is electrically connected with boss 20. The current flows through the boss 20, microphone electrode 25 diaphragm 26, conducting casing 13 to strip 38 and out to battery at terminal 11. By varying the position of the switch 35 more or less of the resistance coils 31 can be thrown in or out and the strength of current can be controlled as will be readily understood. Under the end of the end of the switch 35 which carries the handle 36 there is preferably placed a sector shaped sheet of insulating material 40 to insulate the switch from the casing. The switch also has a struck up portion 41 which contacts with the boss and maintains the operating button without the slot in the cover plate.

What I claim as the invention of the said

25 EUGENE W. SCHNEIDER, deceased, is:

1. In a telephonic apparatus for aiding the hearing, the combination of a transmitter having a conducting casing, a boss centrally disposed in the rear wall of the said 30 casing, a microphone electrode secured thereto, a series of resistance coils within the casing, an arcuate insulating block in the back wall of the casing, taps and contact points therein, said taps being connected with resistance coils, said contact points being concentrically disposed about the said boss and a switch arm pivoted upon the outer end of the said boss and adapted to be shifted to contact with any desired contact

5 point whereby the strength of current 40 through the microphone is controlled.

2. In a telephonic apparatus for aiding the hearing in combination, a transmitter having a conducting casing, a microphone electrode therein, a rheostat for varying the 45 strength of current passing therethrough, said rheostat comprising a plurality of coils of resistance wire, a plurality of taps leading therefrom, contact points connected with the said taps, a switch adapted to be rotated to contact with any one of the contact points, said switch being adapted to bridge over two contacts whereby the circuit is never broken, a cover plate having an arcuate slot therein mounted upon the rear of 50 the said casing and a switch handle attached to the switch and projecting through the said arcuate slot into a position accessible to the user.

3. In a telephonic apparatus for aiding the 60 hearing in combination a transmitter having a conducting casing, a conducting boss in the center of the rear wall of the said casing and insulated therefrom, and arcuate 65 insulating block concentrically disposed about the said boss, concentrically arranged contact points therein, resistance coils and taps connecting the coils with the contact points, a switch arm pivoted upon the said boss and adapted to make a contact with 70 each of the said contact points a cover plate, an arcuate slot therein and a switch operating handle carried by the switch and projecting through the arcuate slot in the cover plate.

ELIZABETH C. SCHNEIDER,
Executrix of Eugene W. Schneider, deceased.
